attorney.

UNITED STATES PATENT OFFICE.

EARL WEST, OF OAKLAND, CALIFORNIA.

CLOTHESPIN.

1,407,344.

Specification of Letters Patent. Patented Feb. 21, 1922.

Application filed March 28, 1921. Serial No. 456,054.

To all whom it may concern:

Be it known that I, EARL WEST, a citizen of the United States of America, residing at Oakland, in the county of Alameda and 5 State of California, have invented new and useful Improvements in Clothespins, of which the following is a specification.

This invention relates to devices for retaining articles, such as clothes, on a clothes 10 line, and has for its object the provision of means whereby positive wedging action of said means will accomplish the desired result.

A further object of this invention is to 15 provide a device of the character described, which has means associated with the parts comprising the same for preventing said parts from being accidentally displaced from each other.

20 Another object of this invention is to provide a device of this character which is simple in construction, inexpensive to manufacture, strong, durable and reliable in operation.

25 Other objects and advantages will be apparent during the course of the following description.

In the accompanying drawings forming a part of this specification and in which 30 like numerals are employed to designate like parts throughout the same,

Figure 1 is a perspective view of the device shown applied to a clothes line,

Figure 2 is a similar view showing the 35 device detached from the line.

Figure 3 is cross-section of the device, and

Figure 4 is an enlarged sectional detail of the invention, showing an end cap positioned therein.

40 In the drawings wherein for the purpose of illustration is shown a preferred embodiment of my invention the numeral 5 designates a tubular body of preferably made wood which has provided therein a longitudinal bore 6 and recesses 7. This body 5 is likewise equipped with an extension 8 which has formed therein a transverse groove 9 and thereon a beveled upper surface 10, adapted to be received in the groove 50 9, is a clothes line 11, on which is placed an article 12, to be suspended. In actual practise the article rests on the line and part of the same is then draped over the beveled surface, after which action it is held in a 55 fixed position through the wedging contact of a pin 13, also preferably made of wood.

As shown to advantage in Figures 2 and

3 this pin is preferably cylindrical in form and tapered from a part extending half its length to its extremity 14, in order to assure the wedging effect when the pin is moved inwardly, from the bore 6, of the body 5.

For the purpose of retaining the pin 13, in the body 5, to prevent its accidental displacement therefrom, I have provided a slot 14, adapted to extend from the rear extremity of the pin to the point 15, which is over three-fourths the length thereof, and have suitably mounted in the tubular body a vertical disposed cross-pin 16, this cross pin extends from the slot 14, and has its respective ends mounted in recesses 7 formed in the body 5.

From the consideration of Figure 3 of 75 the drawing it will be apparent that inward movement of the pin 13, in the body 5, will be limited by the contact of the cross-pin 16, with the body portion of the tapered pin 13, at the point 15, and thus prevent 80 the above mentioned accidental displacement.

In order to render the tapered slotted pin 13, compact throughout its length and also strong at its rear extremity I propose to 85 suitably mount a gear 17, on the rear end of the pin.

It is to be understood that the form of my invention, herewith shown and described, is to be taken as a preferred example of the same, and that various changes in the shape, size and arrangement of parts, may be resorted to without departing from the spirit of the invention, or the scope of the subjoined claim.

Having thus described my invention, I claim:

A clothes pin comprising a tubular body terminating in an extension having a beveled upper surface, a tapered slotted pin 100 slidably mounted in said body for longitudinal movement therein, said pin being adapted to wedge an article resting on a clothes line between the tapered surface of the pin and the beveled surface of said body, 105 a cross pin positioned in said body and entering the slotted portion of said tapered pin to prevent accidental displacement of the same from said body, and means positioned on the rear of said tapered pin to prevent 110 its extraction from said body.

In testimony whereof I affix my signature.

EARL WEST.
